Fraenzer and Richards
ATTORNEYS.

UNITED STATES PATENT OFFICE.

HUGO TUECKMANTEL, OF IRVINGTON, NEW JERSEY, ASSIGNOR TO THE R. NEUMANN HARDWARE CO., A CORPORATION OF NEW JERSEY.

BAG FRAME.

Application filed September 2, 1920. Serial No. 407,703.

To all whom it may concern:

Be it known that I, HUGO TUECKMANTEL, citizen of the United States, residing at Irvington, in the county of Essex and State 5 of New Jersey, have invented certain new and useful Improvements in Bag Frames; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in frames for travelling bags, and the like; and, the present invention has references, more particularly, to a novel construction of bag-frame, comprising a 20 pair of pivotally connected or hinged frame-sections, one of which, and which is termed the outer frame-section, being of greater width than the other frame section, which is termed the inner frame-section, and is 25 adapted to enter within the outer frame section, when the said frame-sections are brought into their closed relation.

The two frame-sections are each L-shaped in cross-section, and in practise, a lock- 30 casing is mounted within the outer frame-section, and a hasp-plate provided with the usual lock-engaging hasp or hasps is mounted within the inner frame-section.

Now, it has been found in practice, to 35 provide the outer frame-section with a lock-mechanism of considerable strength, requiring a substantially large-lock casing, that the width across the upper member of the inner frame-section is such, that when the 40 frame-sections are closed, the marginal edge of the inner frame-section would strike the large lock-casing and prevent the complete closing of the frame-sections, or, if closed, would produce a distorted relation of the 45 inner frame-section within the outer frame-section.

To overcome these objections, the upper member of the inner frame-section is partially cut away, so that said member is 50 fitted around the lock-casing as the two frame-sections are closed.

This recessed or cut-away edge-portion of the inner frame-section, may, however, weaken said frame-section at said location,

and to strengthen the said frame-section at 55 such cut-away portion, the vertical member of the inner frame-section is strengthened by a re-enforcing plate which is suitably secured to the said vertical member, the said re-enforcing plate being provided with 60 a hasp-lug or lugs, adapted to enter the lock-casing and engage the lock-mechanism contained in the said casing.

The present invention, therefore, has for 65 its principal object to provide a simply constructed bag-frame, the frame-sections thereof being made so that the purposes hereinabove stated are fully carried out, and, furthermore that a bag-frame having a lock of 70 large proportion will be provided, and the frame-sections of which can be properly closed so as to provide a bag-frame of neat appearance.

Other objects of the present invention not 75 at this time more particularly enumerated will be clearly understood from the following detailed description of the present invention.

With the various objects of the present invention in view, the said invention consists, primarily, in the novel bag-frame, comprising a pair of frame-sections of the general character hereinafter more fully set forth; and, the said invention consists, furthermore, in the novel arrangements and 85 combinations of the various devices and parts, as well as in the details of the construction of the said parts, all of which will be more fully described in the following 90 specification, and then finally embodied in the clauses of the claims which are appended to and which form an essential part of the 95 said specification.

The invention is illustrated in the accompanying drawings, in which:—

Figure 1 is a top or plan view of the central portion of a bag-frame, with the inner frame-section closed within the outer frame-section; Figure 2 is a bottom view of the said fragmentary portions of the two frame-sections represented in their closed relation; and Figure 3 is a top or plan view of the said fragmentary portions of the frame-sections, represented in their unlocked and open relation.

Figure 4 is a detail face view of the inner 100 face of the inner frame-section, showing one manner of securing the re-enforcing hasp-

plate and its hasp-lugs to said frame-section; and Figure 5 is a transverse vertical section of the two frame-sections, said section being taken on line 5—5 in Figure 1, 5 looking in the direction of the arrow X, with the lock-casing represented in end elevation.

Similar characters of reference are employed in the said above described views, 10 to indicate corresponding parts.

In the said drawings, the reference-character 1 indicates a fragmentary portion of the central part of the outer frame-section, and 2 indicates a similar portion of the central part of the inner frame-section.

As herein-above stated, both frame-sections are L-shaped in cross-section, the outer frame-section comprising the usual wide top-member 3 and the vertical member 4, 20 and the inner frame-section comprising the narrow top-member 5 and the vertical member 6. As shown in Figures 1 and 3 of the drawings, the top-member 3 of the outer frame-section 1 is made with a centrally disposed key-post receiving opening, as 7, into and through which the key-post 8 of the lock-mechanism extends. The said key-post 8 is connected with and extends from a suitably formed lock-box or casing 9, which is 30 provided at its ends with the usual box-extensions 10, each extension having a perforated lug or ear 11 for the reception of rivets 12 for securing the lock-box or casing against the vertical member 4 of the outer frame-section 1. That the said lock-box or casing 9 may be properly centered beneath the top-member 3 of the frame-section 1, washers 13 of suitable thickness may be mounted upon the rivets 12 between the lugs 35 or ears 11 and the vertical member 4 of the frame-section 1, substantially in the manner illustrated in Figures 2 and 5 of the drawings.

That the inner frame-section 2 may be 45 properly and neatly disposed within the outer frame-section 1, when the two frame-sections are in their closed relation, the central portion of the marginal edge 14 of the top-member 5 of the said inner frame-section 2, is sufficiently cut away so as to provide a marginal recess, as 15, which is adapted to embrace the side-face and the ends of the lock-box or casing 9, and thereby acts as a stop, substantially as shown in said 50 Figures 2 and 5, and whereby the two frame-sections, when closed, are brought into perfect registration with one another, so that the closed inner frame-section 2 will not extend beyond the marginal edge 16 of the top-member 3 of the frame-section 1, and, furthermore, that any distorted relation of the two closed frame-sections can not occur. Since this recessed or cut-away portion 15 in the top-member 5 of the inner frame-section might possibly weaken said frame-section.

tion, I have secured, by means of rivets 17, or in any suitable manner, to the inner face of the vertical inember 6 of said frame-section 2, and at a point in alinement with said recess or cut-away portion 15, a strengthening plate 18 which is provided along its lower marginal edge with a re-enforcing rib or right-angled member, as 19, said member 19 being fitted directly upon the marginal edge-portion 20 of the said vertical member 6, in a manner as clearly illustrated in Figures 2, 4 and 5 of the drawings. In addition to this re-enforcing rib 19, the said plate 18 is also provided with suitably disposed hasp-lugs or ears, as 21, which, when 70 the inner frame-section 2 enters into closing relation with the outer frame-section 1, enter suitably disposed openings in the side of the lock-box or casing 9, for locking engagement with the lock-mechanism within said box or 85 casing 9, in any usual and well-known manner.

Having in the foregoing specification described the general constructions of the pivoted or hinged frame-sections for travelling bags and the like, and in connection therewith the general arrangement of the bag-lock and re-enforcing hasp-plate, any further description of the said various devices and their parts is deemed unnecessary.

Of course I am aware, that some changes may be made in the general arrangements and combinations of the said various devices and parts, as well as in the details of the construction of the same, without departing from the scope of the present invention as set forth in the foregoing specification, and as defined in the clauses of the claims which are appended thereto. Hence, I do not limit my present invention to the exact arrangements and combinations of the said devices and parts as described in the said specification, nor do I confine myself to the exact details of the construction of the said parts, as illustrated in the accompanying drawings.

I claim:—

1. A bag-frame comprising an outer and an inner frame-section, each frame-section having a top-member and a vertical side-member, the top-member of the outer frame-section being of greater width than the top-member of the inner frame-section, and a bag-lock comprising a box secured to the vertical side-member of said outer frame-section, the top-member of said inner frame-section having a marginal cut-away portion adapted to embrace said box to thereby act as a stop when the frame-sections are in their closed relation, combined with a re-enforcing hasp-lug plate secured to the inner face of the vertical side-member of said inner frame-section in alinement with the cut-away portion in the top-member of said inner frame-section, and a marginal rib ex- 130

tending from said plate, said rib being located upon a portion of the marginal edge of the vertical member of said inner frame-section.

- 5 2. A frame-section for bag-frames comprising a top-member and a vertical side-member, said top-member being provided with a marginal lock-box receiving cut-away portion, a re-enforcing hasp-lug plate secured to the inner face of the vertical side-member of said frame-section in alinement with the cut-away portion in the top-mem-
- 10

ber of said frame-section, and a marginal rib extending from said plate, said rib being located upon a portion of the marginal edge of the vertical side-member of said frame-section.

In testimony, that I claim the invention set forth above I have hereunto set my hand this 31st day of August, 1920.

HUGO TUECKMANTEL.
